UNITED STATES PATENT OFFICE.

CHARLES J. KENNEDY, OF DULUTH, MINNESOTA, ASSIGNOR TO NORTHERN NOVELTY MANUFACTURING COMPANY, OF DULUTH, MINNESOTA, A CORPORATION OF SOUTH DAKOTA.

INSTRUMENT.

1,225,969.

Specification of Letters Patent.

Patented May 15, 1917.

Application filed June 1, 1916. Serial No. 101,008.

To all whom it may concern:

Be it known that I, CHARLES J. KENNEDY, a citizen of the United States, residing at Duluth, in the county of St. Louis and State of Minnesota, have invented certain new and useful Improvements in Instruments, of which the following is a specification, reference being had therein to the accompanying drawing.

10 This invention consists of certain improvements in instruments and relates especially to a cleansing instrument for cleaning and drying safety razor blades.

15 The object is to produce a simple and sanitary device of this nature, cheap in construction and convenient in operation.

Referring to the drawings in which like reference characters indicate like parts:

20 Figure 1 is a perspective view of my improved instrument, and

Fig. 2 represents a modified form of same.

Referring to Fig. 1, 1 represents the body of the instrument having the flat portion 2 widened transversely and at the opposite 25 end formed into the cylindrical handle socket, 3.

The flat portion 2 is in general outline rectangular in form and has securely fastened thereto upon one side, either by rivets 30 indicated at 4 or suitable adhesive substance, a preferably rectangular shaped piece 5 of non-absorbent substance, such as rubber or the like and upon the opposite side is suitably fastened a similarly shaped piece 35 6 of absorbent material, such as felt or the like.

Adjacent the rear corners of the pads 5 and 6 and formed integral with the flattened portion 2 of the body of the instrument, are 40 illustrated lugs, 7 and 8 projecting at right angles to the faces of the portion 2, two upon one side and two upon the other.

These lugs are sufficiently long to extend beyond the surfaces of the pads when in place, and are for the purpose of supporting the padded end of the instrument when at rest upon the dresser or table.

45 The object of providing such support is to keep the pads from contacting any foreign object such as the dresser or table top whereby they might become fouled, or when, after being used they might soil the object upon which the instrument is placed.

While I have shown the lugs 7 and 8 as 50 being formed integral with the flattened

portion 2 of the instrument, it is evident that one or more small pins may be used in lieu thereof and said pins being made to fit snugly within holes formed through the flattened portion 2 and allowed to project above the face of the pads, or other similar arrangement may be resorted to.

The non-porous or non-absorbent pad 5 is for the express purpose of removing by forcible frictional contact as nearly as possible all foreign substances from the razor blade when wiped therewith and the porous or absorbent pad upon the opposite side is for the purpose of further cleansing the blade and at the same time drying it. The 70 cleansing and drying operation, under normal conditions, require but a single wipe by each pad, to complete a substantially perfect job.

While I have shown the handle 7 as being of a separate piece of material, it is evident that the entire body and handle may be formed of a single piece, as illustrated in Fig. 2 of the drawings, or in other forms as desired without departing from the spirit of the invention.

Having thus described my invention what I claim and desire to secure by Letters Patent, is:

1. An instrument of the character described, comprising a handle portion, a thin flattened portion fixed to the handle and having the faces thereof parallel, pads of different character fixed to the opposite faces of the flattened portion and means 85 adjacent the innermost edges of the pads for supporting the instrument when not in use.

2. An instrument of the character described, comprising a cylindrical shaped 95 body portion having a handle at one end, the opposite end flattened to a rectangular shape transverse the body portion, the two faces of said flattened portion being parallel, pads fixed to the opposite faces of the 100 flattened portion and means for preventing the pads from contacting the object upon which the instrument rests when not in use.

In testimony whereof I hereunto affix my 105 signature in the presence of two witnesses.

CHARLES J. KENNEDY.
